UNITED STATES PATENT OFFICE.

THOMAS L. McGREGOR, OF MILWAUKEE, WISCONSIN.

STEAM-BOILER.

SPECIFICATION forming part of Letters Patent No. 556,473, dated March 17, 1896.

Application filed July 10, 1895. Serial No. 555,476. (No model.)

To all whom it may concern:

Be it known that I, THOMAS L. McGREGOR, a citizen of the United States, and a resident of Milwaukee, in the county of Milwaukee and 5 State of Wisconsin, have invented certain new and useful Improvements in Steam-Boilers; and I do hereby declare that the following is a full, clear, and exact description thereof.

My invention relates to steam-boilers of the 10 kind usually known as "water-tube" boilers; and it consists in certain peculiarities of construction and combination of parts, as will be fully set forth hereinafter and subsequently claimed.

15 In the drawings, Figure 1 is a representation of my device partly in side elevation and partly in section. Figs. 2 and 3 are sectional views on the lines 2 2 and 3 3, respectively, of Fig. 1.

20 Referring to the drawings, A represents the front wall, and B the rear wall, of suitable masonry, such as brick, which serves to inclose my boiler.

C is the bridge-wall, and D the grate of the 25 fire-bed.

E represents a partition-wall of brick supported on a metallic plate e that extends from side to side of the structure.

F is the top wall, and f the smoke-flue or 30 chimney. The rear wall, B, has a door b for convenient access to the rear end of the boiler, and the front wall, A, a like door a for access to the front end of the boiler, and below this door are shown other doors, c and d, for putting in the fuel and for taking out the ashes, 35 respectively.

Referring now particularly to the boiler, G represents the front water and steam chamber of semicircular shape in cross-section, as 40 shown in Fig. 2.

H is the rear water-chamber, of similar shape in its main part, extending down to the lower part of the structure, while the chamber G extends from a point above the fire-bed to 45 the top of the structure. Both of these chambers are obliquely arranged and connected by tubes g g g obliquely arranged at the same angle. The water-chamber H has a vertical upward-extending pipe h of reduced diameter, which forms practically part of said rear 50 water-chamber, and which communicates at its top with the rear end of the horizontally-

disposed steam-drum I, which latter, at its front end, communicates with the rear face of the upper part of the water-chamber G. 55 The said chamber G has a manhole i with suitable plate and closing device j in line with door a, and the chamber H has a like man-hole k with like plate and closing device m in line with door b. A blow-off pipe J extends 60 from the bottom of the chamber G out through the rear wall, B, and L represents the feed-water inlet-pipe extending through said rear wall and into the part h of the rear water-chamber, H, preferably just above the top of 65 the main part of said water-chamber.

M is the steam-outlet pipe, and N the safety-valve pipe, both leading upward from the steam-drum I.

The operation of my device will be readily 70 understood from the foregoing description of its construction. The feed-water is admitted through the pipe L into the coolest part of the boiler, which is a great advantage, as thereby the impurities contained in the water will 75 drop down to the bottom of the chamber H, from whence they can be blown out through the pipe J without ever getting into the tubes g g, whereas when the feed-water is introduced at the front of the boiler over the fire-bed the impurities therein contained become 80 coated by the heat upon the surfaces of the water-chamber and tubes of the boiler.

As my feed-water inlet-pipe merely extends through the rear wall of the part h of the rear 85 water-chamber, as shown in Fig. 1, instead of continuing in loops, bends, or coils within said water-chamber, there is no opportunity for said pipe to become clogged up with any impurities; but everything therein contained 90 will at once drop out and fall down to the bottom of said water-chamber, as stated.

Another advantage of my device lies in the semicircular form shown and described of my water-chambers, as thereby they may be made 95 of sufficient capacity without unduly extending them vertically. Again, I find it of advantage to connect the steam-drum as shown, instead of leading it from the top of the front water-chamber, as vertical space is saved and 100 the device rendered consequently more compact, while at the same time my said steam-drum serves to brace and strengthen the front water-chamber.

Having thus described my invention, what I claim as new, and desire to secure by Letters Patent, is—

1. In a tubular boiler, the combination with a fire-bed, of an obliquely-arranged front water and steam chamber supported above said bed, an obliquely-arranged rear water-chamber extending below the plane of the front chamber, obliquely-arranged water-tubes connecting the two chambers, a horizontally-disposed steam-drum connected to the rear upper side of the front chamber and with the steam-space thereof, and connecting by a vertical pipe with the rear chamber, and a feed-water-inlet pipe arranged to communicate with the rear water-chamber at the rear thereof without extending within said chamber, whereby the feed-water will always be received at the coolest part of the boiler and the said inlet-pipe be kept free from scale and other impurities, substantially as set forth.

2. In a tubular boiler, the combination of an obliquely-arranged front water and steam chamber, having a steam-space in its upper end, and an obliquely-arranged rear water-chamber, both semicircular in horizontal cross-section, obliquely-arranged water-tubes connecting the two chambers, a vertical pipe rising from the rear chamber and a horizontally-disposed steam-drum communicating with the top of said pipe, and with the steam-space in the upper end of the front chamber below the top thereof, substantially as set forth. 25 30

In testimony that I claim the foregoing I have hereunto set my hand, at Milwaukee, in the county of Milwaukee and State of Wisconsin, in the presence of two witnesses.

THOMAS L. McGREGOR.
